SERVOMOTOR CONTROL

Walter Ernst, Mount Gilead, Ohio, assignor, by
mesne assignments, to The Hydraulic Press
Corporation, Inc., Wilmington, Del., a corpo-
ration of Delaware

Application October 21, 1932, Serial No. 638,905

2 Claims. (Cl. 103—38)

This invention relates to control mechanism for regulating the flow of variable discharge pumps and other hydraulic machines having movable flow-controlling elements.

One object of this invention is to provide a simple, efficient and highly responsive flow-control mechanism for a variable discharge pump, in which the flow will be automatically controlled to meet the exact operating requirements.

A further object is to provide a simple and efficient means for limiting the maximum discharge pressure of the pump.

A further object is to provide means for adjusting the regulating or control means, so that it may be made to operate at any desired predetermined pressure.

In the drawings:

Figure 1 is a diagrammatic view of the circuits, showing a pump with the control and actuating valves in longitudinal cross section.

Figure 2 is a similar view showing a pump with adjustable means for limiting its maximum discharge pressure, the control unit being shown in elevation, and the press and compensating valve and its connections being omitted.

In order to illustrate more clearly the construction, the drawings show the control and actuating units as disproportionately large relative to the size of the pump.

Referring to the drawings in detail, 1 indicates any suitable reversible variable-discharge type of pump with a discharge control element or shifter ring 1a and connected, through suitable fluid pressure circuits, with a machine having a movable member of any desired kind, for moving that member in any operation in which such movement may be a factor. As a familiar example of such a machine, an ordinary hydraulic press is illustrated, comprising a press cylinder 2, and a piston 3 reciprocable therein. Piston 3 is provided with a piston rod 4, which carries a ram 5 cooperating in the usual manner with the stationary press member or anvil 6. The cylinder 2 and anvil 6 may, as usual, be part of or suitably carried by the press frame 7. A wide range of other types of reciprocable or otherwise movable parts may be substituted for the press here shown without departing from the scope of the invention.

Throughout the application, unless the context clearly indicates otherwise, the term fluid is to be construed broadly as including all fluids applicable to the field of use. Wherever a definite fluid is named, such as oil, unless the context clearly indicates otherwise, it is to be under-

stood as including all other fluids, as above stated.

The flow of the pump 1 may be changed in direction by moving the shifter ring or discharge control element 1a in one direction or the other from its neutral position in which the pump runs idle or without delivery. The degree or rate of flow in either direction will be in proportion to the movement of the shifter ring 1a. The means for accomplishing this shifting is well known to those skilled in the art and, therefore, requires no detailed description in the present application. Figure 1 shows the shifter ring of the pump in its neutral position, the pump running idle without discharge in either direction.

Connected in any suitable manner to the shifter ring of the pump, and extending toward the left in Figure 1, is a piston or valve member 8 provided with two longitudinally spaced heads 9 and 10. The piston rod 8 is also provided with a longitudinal bore 11 running from its free end lengthwise toward its connected end and terminating in a port 12 beyond the innermost head 10. Surrounding the valve member 8 is a reciprocable sleeve 13 provided with a perforated ear 14 by which it may be connected to a suitable link 15. The opposite end of the link 15 is connected to a hand lever 16 suitably mounted in the bracket 18. The hand lever 16 is provided with the usual spring-actuated pawl engaging the cooperating ratchet plate 17 to lock the lever in various adjusted positions. In order to adjust the movement of the sleeve, a turnbuckle or other similar connection may be used between the lever and the sleeve end. The form shown comprises two clevises 19, each being threaded onto the end of the link 15 and connected to the lever and sleeve respectively. Stop nuts are also turned on the link 15 to engage the clevises 19 and prevent them from traveling beyond their set positions.

The sleeve 13 is reciprocable in the control valve casing 20, which has a central bore 21 to slidably receive the sleeve, and three longitudinally spaced annular chambers 22, 23 and 24. Sleeve 13 is provided with ports 25, 26, and 27 through its side walls and adapted to register with the annular chambers 22, 23, and 24. The ports 25, 26 and 27 are so spaced that 25 and 27 may be registered with and closed by the heads 9 and 10, respectively, of the valve member 8. The inner bore of the sleeve 13 is of such length as to leave a chamber 28 at its end. The control valve casing 20 is of such length relative to sleeve 13 as to provide a chamber 28 beyond the end of the sleeve when

said sleeve is in its innermost operative position. The bore 11 in valve member 8 is of such length that its outlet port 12 will at all times communicate with chamber 29. Since the bore 11 extends from port 12 completely through the valve member 8, it establishes communication between the chambers 28 and 29. The control valve casting 20 is provided with lateral bores or passages 30, 31, 32 and 33 communicating with chambers 10 22, 23, 24, and 29, respectively.

The movement of the sleeve 13 relative to the valve member 8 or vice versa, controls the passage of fluid through the control valve and thence through the lines 58 and 59 leading to the actuating unit of the servomotor. Communicating with chamber 23 is the pressure line 34 through which servomotor fluid is supplied under low pressure by a suitable gear pump 35 or other suitable supply medium. Pump 35 draws its fluid through 20 the suction line 36 from the tank 37 or other reservoir. To avoid possible strain or overload in line 34 or pump 35, a branch 38 is provided establishing communication between pressure line 34 and the tank 37 through a relief valve 39 to 25 permit excess fluid to return to tank 37. An exhaust line 40 leads from the bore 33 at the end of chamber 29 to the tank 37. Thus with the parts in the neutral position of Figure 1, the low pressure servomotor fluid from the pump 35 30 will circulate from the tank through the pump and back to the tank by the branch line 38 and relief valve 39.

The actuating unit of the servomotor is mounted on the opposite side of the pump from the control valve. It comprises a piston rod 41 reciprocably mounted in the actuating piston casting, and connected in any suitable manner to the shifter ring of the pump 1 at a point opposite the connection between the valve member 8 40 and the same ring. The piston rod 41 is provided with an enlarged cylindrical portion which provides an annular shoulder 43. This annular shoulder 43 is reciprocably mounted in the chamber 44 provided with a lateral communicating bore or passage 45, for a purpose to be later disclosed. To the opposite or outer end of the piston rod 41 is secured a piston 46 reciprocable in the cylinder 47 of the casing 42. The cylinder 47 is provided with lateral ports 48 and 49 near its opposite ends for delivery of pressure fluid to or from the opposite sides of the piston 46. The cylinder head 50 of cylinder 47 is provided with a bore or chamber 51 in which is reciprocably mounted a pilot piston 52 of sufficient length to 50 remain in contact with piston 46 in all of its positions within its cylinder 47 and yet remain partly within and guided by the chamber 51. A port 53 in the outer end of chamber 51 serves for admission and exhaust of fluid to actuate the pilot piston 52.

From the pump 1, the two power lines 54 and 55 lead to the pressing and pullback sides, respectively, of the press piston 3 to move the ram downward during its pressing operation or to return it upward during the pullback operation. From the line 54 a branch 57 leads to the bore 45 of chamber 44. From the line 55 a branch 56 leads through port 53 into the chamber 51 of the pilot piston. Servomotor pressure line 58 establishes communication between bores or passages 32 and 48. Servomotor line 59 establishes communication between bores or passages 30 and 49.

To compensate for the differences in area between the upper and lower faces of piston 3, a 75 two-way compensating valve 60 connects the

power lines and is provided with a branch 61 leading back to the tank 37, as is disclosed in my United States Patents 1,653,350 and 1,861,116, to both of which reference is hereby made.

To perform a pressing stroke with the parts in the positions of Figure 1, the lever 16 is swung to move the sleeve 13 toward the left. This will uncover the opening 27 which is in communication with chamber 24. Servomotor pressure fluid will then pass through the sleeve 13 and chamber 10 24 and into the servomotor line 58, entering the cylinder 47 to the right of the piston 46 and moving it to the left. As it moves to the left, fluid on the opposite side of piston 46 will exhaust through port 49 into servomotor line 59, thence by way of bore 30, chamber 22, and chamber 28, bore 11, port 12, chamber 29 and exhaust line 40, back to the tank 37. This movement of piston 46 carries the pump shifter ring from its neutral position of Figure 1 into a discharge position where 20 the pump will force power fluid through the line 54 to the upper side of the piston 3, starting the pressing stroke of the hydraulic press.

As the piston rod 41 travels toward the left under the influence of the servomotor fluid and carries the shifter ring with it, the valve member 8 at the opposite side of the ring will be correspondingly moved toward the left. The piston heads 9 and 10 will thus again shut off the respective ports or openings through the sleeve 13 30 into the servomotor lines 58 and 59, but flow of power fluid through the power lines 54 and 55 will continue, as established by the movement of the shifting ring 1a. Thus the movement of the valve sleeve 13 establishes the rate or magnitude of the flow in the power lines 54 and 55. The pump may be run in the opposite direction simply by shifting sleeve 13 so that the flow through the servomotor lines 58 and 59 will be reversed, as will be readily understood. To do this, the pump 40 is brought back through its neutral position in an obvious manner.

Should there be an overload in the pull-back or return line 55 and the pressure built up beyond a predetermined point, this excess pressure 45 will be transmitted through the branch line 56 to the end of pilot piston 52, forcing it inward and moving piston 46 toward the left. This, of course, will carry the shifter ring of the pump to the left toward its neutral position thereby 50 reducing the discharge of the pump and lowering the pressure in the return line 55. The excess discharge of the servomotor pump 35 at such time returns to the tank 37 through its relief valve 39.

Should there be an overload in the pressing or working line 54, the excess pressure will be transmitted through branch line 57 into the chamber 44 where it will act on the annular shoulder 43 moving piston rod 41 to the right. 60 This, in turn moves the shifter ring 1a to the right toward its neutral position, thereby reducing the discharge of the pump and lowering the pressure in the pressing line 54. The excess discharge of the servomotor pump 35 at this time 65 returns as before to the tank 37 through its relief valve 39.

It will be seen that there is thorough and adequate overload protection for both pressing and pull-back operations. This protection is entirely 70 automatic and may be made very sensitive. The active pressure receiving areas of the pilot piston 52 and shoulder 43 are so proportioned, of course, as to operate their respective piston members when a predetermined overload or excess 75

pressure is reached in the respective main power lines 54 and 55 and their corresponding branches 57 and 56, respectively. The overload actuated elements in both instances return the pump to its neutral position.

Figure 2 illustrates an arrangement in which the actuating unit of the servomotor embodies means for selectively and adjustably setting the mechanism to operate automatically at any one of a wide range of different pressures, as may be desired under various circumstances and conditions. In this arrangement, the entire control unit and its circuits (to the left of the pump) are the same as in Figure 1 and operate in the same way. The piston rod 41 is also connected to the pump shifter ring 1a in the same way and for the same purpose as in Figure 1. However, instead of carrying a single piston, the machine of Figure 2 carries a casing 100 having two cylindrical chambers 101 in which are reciprocably mounted pistons 102 provided with piston rods 103. The piston rods 103 are secured to a yoke 104 slidably mounted on piston rod 41 and adapted to seat against a shoulder or other suitable stop 105. The yoke 104 is held yieldingly in engagement with the stop 105 by a coil spring 106 or other suitable variable pressure means. Casing 100 is suitably anchored on the bed of the pump or other suitable foundation. A cup 107 is slidably mounted on the piston rod 41 and encloses the spring 106. In order to vary the compression of spring 106, a hand wheel 108 or other means is adjustably mounted, as by screw threading, upon the outer end of the piston rod 41. Suitable anti-friction bearings are interposed between the hand wheel 108 and the adjacent end of the spring cup 107. A nut or other stop element may be provided on the extreme end of piston rod 41, to retain the hand wheel thereon.

The piston rod 41 is enlarged to provide a piston shoulder 110 within the pressure chamber 111 of the casing 109. Two other pressure chambers 112 in the casing 109 are adapted to reciprocably receive pilot pistons 113, each of which is adapted to engage the end of the corresponding piston rod 103. The movement of the pistons 102 toward the left is resisted by fluid pressure in the chambers 112 acting on pistons 113 also by fluid pressure in the left ends of the cylinders 101. The action of the spring 106 and of pressure fluid within the chamber 111 will oppose this tendency. As described above, this opposing force may be varied and regulated by turning the hand wheel 108.

In Figure 2, as in Figure 1, the parts are shown in the neutral position of the pump. In order to move the piston rod 41 toward the left, the sleeve 13 is moved to the left, allowing fluid pressure to pass into the servomotor line 58, thence through the ports 48 into the two cylinders 101. To move the piston rod 41 toward the right, as in Figure 1, the sleeve 13 is also moved toward the right, allowing fluid pressure to pass through the servomotor line 59 into the two cylinders 101 through the ports 49, by way of the branch pipe connecting them.

In case of an overload or excess pressure in the pull-back line 55, relief is provided, as in Figure 1, by causing this pressure to pass through branch 56 into chamber 111 acting on the pilot piston shoulder 110 to return the pump shift ring 1a toward its neutral position. Similar relief in the pressing line 54 is provided through branch 57, communicating with both chambers 112

through ports 45; the excess pressure acts upon pilot pistons 113 to force the pump shift ring toward its neutral position. The operations are substantially the same as previously described in connection with Figure 1 and therefore will not be repeated in detail.

Thus it will be seen that I have provided a servomotor for hydraulic machinery which is very compact and of few parts. The servomotor mechanism is arranged in substantially a straight line passing diametrically through the pump shifter ring, and auxiliary pistons and floating levers or fulcrums are thereby eliminated. The servomotor valve rod and the piston rod on the opposite side from the valve rod are integrally attached to the shifter ring and move with it as a unit, avoiding the wear and lost motion occasioned by the use of levers or gears. The overload mechanism of my servomotor is likewise of more simple and more rugged construction than has heretofore been used, replacing auxiliary pistons by a simple enlargement of the main piston rod. Accordingly, my servomotor construction represents an increase in efficiency, economy of construction and long life as compared with other previous constructions.

It will be understood that many changes may be made in the construction, arrangement and disposition of the various parts of the invention, within the field of the appended claims, without departing from the scope of the invention. It is meant to include all such modifications within this application. A single application of the idea has been shown merely as an example, and with no thought or intention of limiting the invention thereby.

Having thus described my invention, what I claim and wish to protect by Letters Patent is:—

1. A control mechanism for a variable discharge pump of the type including a movable pump discharge control element, said mechanism comprising in combination with said control element; a cylinder, a piston therein, a piston rod rigidly connecting said discharge control element and said piston, overload responsive means associated with said piston rod and responsive to the pump discharge to shift said piston rod and said discharge control element to the no-discharge position thereof, a valve assembly comprising a valve housing and a pair of cooperating valve elements in said valve housing, one of said valve elements being rigidly connected to said discharge control element, the second valve element being adjustably mounted relatively thereto, means for shifting said second valve element, and conduits interconnecting the valve assembly and the cylinder, whereby actuation of said second valve element will admit fluid to said cylinder to cause said piston to actuate said discharge control element to vary the pump discharge and to actuate the first valve element in follow-up relationship to said second valve element without lost motion between said elements.

2. A control mechanism for a variable discharge pump of the type including a movable pump discharge control element, said mechanism comprising in combination with said control element; a cylinder, a piston therein, a piston rod rigidly connecting said discharge control element and said piston, overload responsive means associated with said piston rod and responsive to the pump discharge to shift said piston rod and said discharge control element to the no-discharge position thereof, a valve assembly com-

prising a valve housing and a pair of cooperating valve elements in said valve housing, one of said valve elements being rigidly connected to said discharge control element on the side opposite said piston, the second valve element being adjustably mounted relatively thereto, means for shifting said second valve element, and conduits interconnecting the valve assembly and the cylinder, whereby actuation of said second valve element will admit fluid to said cylinder to cause said piston to actuate said discharge control element to vary the pump discharge and to actuate the first valve element in follow-up relationship to said second valve element without lost motion between said elements.

WALTER ERNST. 5
